- 113

The assembly features a central horizontal plate with various holes and a central gear. On the left, a vertical rod 77 is connected to a lever system. On the right, a large gear 111 is mounted on a shaft, with a smaller gear 112 positioned above it. The drawing uses fine lines and cross-hatching to indicate the three-dimensional structure of the parts.

Inventor:

Edward F. Foster

R. E. Weber

Boyer
C. K. Morris

UNITED STATES PATENT OFFICE.

EDWARD F. FOSTER, OF MILWAUKEE, WISCONSIN.

LABELING MACHINE.

Application filed May 8, 1922. Serial No. 559,403.

To all whom it may concern:

Be it known that I, EDWARD F. FOSTER, a citizen of the United States, and resident of Milwaukee, in the county of Milwaukee and State of Wisconsin, have invented certain new and useful Improvements in Labeling Machines; and I do hereby declare that the following is a full, clear, and exact description thereof.

- 10 The invention relates to devices of the type described in applicant's co-pending application, Serial No. 539,943, filed Feb. 28, 1922, for affixing labels to cakes of soap, or similar objects.
- 15 It comprises means for gripping cakes of soap one by one and overturning them so as to dispose them with the right side up for the reception of a label, a magazine, a suction device for withdrawing the labels one by one from the magazine, and rotary means for directing steam against the adhesive on the label as it is being moved by the suction device so that it is in condition to be affixed to a cake of soap properly guided on an
- 20 endless carrier.

25 The primary object of the invention is the provision of mechanism operative to affix the labels by reason of the softening action of a jet of steam. This does away with the inconveniences of paste troughs and rolls, which needlessly complicate and retard the pasting action and call for considerable work on the part of the operator. The mechanism works automatically, the steam

30 jet being operative for a proper and predetermined interval of time so that the adhesive is softened to a requisite degree. The quantity of steam is definitely and conveniently regulable. There is no excess condensation of the steam adjacent the exit orifices and the application of the steam is made during the travel of the label, which is uninterrupted, the labels being applied in a rapid manner.

40 An additional object of the invention is the provision of a separable magazine, whereby a number of magazines may be used so that when one becomes empty, it may be quickly replaced by another without interrupting operations.

A still further object of the invention is the provision of devices for disposing the cakes of soap properly for the reception of the labels. Means are provided for overturning the cakes so that the overlapping ends of the bands about the cakes may be upwardly disposed.

With the above and other objects in view, which will appear as the description proceeds, my invention resides in the novel & construction, combination and arrangement of parts, substantially as hereinafter described and more particularly defined by the appended claims, it being understood that such changes in the precise embodiment of the herein disclosed invention may be made as come within the scope of the claims.

In the accompanying drawings I have illustrated one complete example of the physical embodiment of the present invention 70 constructed according to the best mode I have so far devised for the practical application of the principles thereof, and in which:—

Figure 1 is a longitudinal, sectional view 71 of an embodiment of the invention showing the steam nozzle in operative position for ejecting steam.

Figure 2 is a plan thereof.

Figure 3 is a cross section on the line 3—3 80 of Figure 1.

Figure 4 is a cross section on the line 4—4 of Figure 1.

Figure 5 is an enlarged view of the devices for overturning the cakes of soap and 85 advancing them, and

Figure 6 is a perspective of a cake of soap with a label applied.

While the invention is capable of use on many objects in the disclosed embodiment, 90 it is adapted particularly for action on cakes of soap 10, which are retained in suitable packages by a band 11 having overlapped ends. The cakes are fed one after another between guides 12—12' on a chute 91 13, which is cut-away at 14 for the reception of a wheel rigid with shaft 15 rotatable in bearing 16 carried by table top 17 and in bearing 18 rigid with table top 19. The wheel comprises a sleeve 20 and integral 10

plates 21 between pairs of which are quadrantual webs 22. Between the webs are openings 23 adapted to receive the cakes of soap one by one.

5 Power for rotating the wheel is transmitted from the main drive shaft 24, which rotates sprocket wheel 25 and thus moves sprocket 26 through the medium of endless chain 27, sprocket 26 rotating shaft 28 supported by leg 29 integral with table top 19. The rotation of shaft 28 moves sprocket 30 rigid therewith, and by means of chain 31 rotates sprocket 32 on shaft 33 mounted to rotate in brace 34. Rigid with shaft 33 is 10 cam 35 having a lifting end 36 on which travels a roller 37 carried by lever 38, the roller being detained at its lowermost position by spring 39 and rotating on pivot 40 carried by the leg 41. Lever 38 carries at 15 one end a pivot 42 on which connection 43 is free to turn pivoted link 44, which, by means of pivot 45, is connected to arm 46 free to rotate on shaft 15. Arm 46 carries a pin 47 on which a dog 48 is movable. 20 When roller 37 is in the position shown in Figure 5, it is at its lowermost point of travel. When cam end 36 moves upwardly, it elevates the roller, thus depressing pivot 42, lowering link 44 and moving 25 dog 48 about a gear 49 rigid with shaft 15. In this movement of the dog, the dog 48 engages the gear 49 and rotates the shaft 15. This downward movement of arm 46 is sufficient to rotate shaft 15 one-quarter 30 of a revolution.

Table top 19 carries guides 50 permitting sliding movement of a reciprocable traveller 51 having a lug 52 thereon to which is pivoted a link 53 pivoted to lever 54 mounted to rotate on pin 55 carried by leg 41. The lower end of the lever is provided with a roller 56 received in a race 57 in cam 35. The race 57 is substantially parallel to the exterior surface of the cam on which 45 roller 37 rides so that the lifting end of the cam is operative to move the lever on pivot 55 and gives a reciprocating motion to traveller 51 so that when a cake of soap is carried in a recess 23 to the table top 19 abutting against guide 58, the movement of traveller 51 kicks the cake out of the recess, the traveler being withdrawn before rotary movement is again imparted to the shaft 15. The provision of quadrantual 50 webs 22 prevents the movement forwardly of cakes 10 until the recess 23 is properly disposed for their reception. The rapid rotation of the shaft 15 is prevented from throwing the soap out of the recesses by 55 the action of retainers 59.

Guide 58 extends longitudinally of table top 19 and is spaced slightly from the inner longitudinal edge thereof. Table top 17 carries a similar parallel guide 58. 60 When the cakes of soap are kicked out of

the recesses 23 by traveler 51, they are engaged by lugs 60 carried by endless chain 27 and moved longitudinally between guides 58-58'. Power shaft 24 has a sprocket wheel thereon operating through a chain 61 to rotate a sprocket 62 rigid with shaft 63 carrying gear 64 meshing with gear 65 on shaft 66. Shafts 63 and 66 are rotatable on a suitable support 67. The rotation of gear 65 operates through a sprocket 68 rigid with shaft 66 to move chain 69, rotating sprocket 70. Sprocket 70 is associated with suction pipe 71 having a valve therein manipulatable by control 72 and the rotation of sprocket 70 operates, by means of cams 73 rigid therewith, to lift the control 72 in a manner fully described in the above identified co-pending application.

The movement of sprocket 70 rotates arms 74 having inlet orifices 75 and gear teeth 76 at their ends. The magazine comprises a cylinder 77 cut-away at 78 in which the labels 79 are stacked. Plunger 80 is operative to urge the labels downwardly. The cylinder carries a pair of oppositely disposed trunnions 81. Table tops 17 and 19 carry supports 82 to which is secured a standard 83 carrying a pair of ears 84, each of which has upwardly directed forks between which trunnions 81 are received. The fork structure permits the ready insertion and withdrawal of a magazine so that a number of magazines may be used and when one becomes empty, it may be conveniently replaced by another which is loaded, so that the operation of feeding the labels may be continued uninterruptedly. The lower end of the magazine is retained normally in its lower position by reason of its greater weight, the position being predetermined by means of an adjustable screw 85 threaded in shoe 86 carried by standard 83. Gear teeth 87 are carried by the lower end of the magazine and mesh with gear teeth 76 on arms 74 so that the rotation of the arms brings the ends thereof adjacent to the end of the magazine, which is rotated on trunnions 81.

As is apparent from the above described co-pending application, the suction acting through arms 74 will draw a single label from the magazine. After the meshing teeth 76 and 87 travel a short distance, they are disengaged and the magazine returns to its normal position, the label continuing its travel. The surface of the label carrying adhesive is disposed outwardly to be acted on by the steam in a manner presently to be described.

Steam is admitted through pipe 88 and elbow 89 in which is received pipe 90 to which sleeve 91 is secured by screw 92 on which hollow shaft 93 is rotatable, the shaft being mounted in bearing 94 carried by support 95 on table top 19. By means of the

- knurled grip 96 on pipe 90, pipe 90 may be rotated on the loosening of bolt 92, thus altering the relationship of slot 97 in pipe 90 to slot 98 in sleeve 91. To admit steam 5 the slots must be in registry, but the size of the exit orifices may be determined by varying the adjustment of the pipe with respect to the sleeve. The rotary shaft 93 carries nozzles 99—99', the opening in which nozzles 10 is brought in registry with the openings 97 and 98 on the rotation of shaft 93. As sprocket 70 has the same angular velocity as shaft 66 and shaft 63 by reason of the sizes of the gears and sprockets, shaft 93 is 15 made to rotate at twice the speed of shaft 63, sprocket 100 being of suitable size to cooperate through chain 101 with sprocket 102 to accomplish this result, shaft 63 being rigid with sprocket 102. Thus there are two rotations of shaft 93 to sprocket 70.
- When the label traveling in a counter-clockwise direction, looking at Figure 1, moves until the arm 74 is disposed toward the left horizontally, the adhesive on the 20 label is exposed to the action of a jet of steam which is emitted through nozzle 99 and orifices 97 and 98. This action is merely momentary, but the duration of time is definitely regulable through the gearing arrangement.
- As described, orifices 97 and 98 operate to regulate the amount of steam ejected. An advantage of having the constriction located at these orifices and at this particular place 25 near the nozzles 99 is that there is a minimum of condensation as the steam is substantially at the point at which it does its work of softening the adhesive on the labels. Pipe 90 is given a slight inclination to carry 30 away water of condensation which drops into pipe 88. When nozzle 99 is moved away from the end of arm 74, such moisture as condenses from the steam is received in a pan 103 carried on rests 104. The moistened 35 label is brought into contact with the center of the cake of soap, covering the overlapped ends of band 11. The soap is moving in the same direction as the label at the time of application of the same. When one label is 40 being applied to the soap, an additional label is being presented to one of the nozzles 99—99'. While there are four arms 74, the fact that nozzles 99—99' travel at twice the speed as the arms 74 results in the 45 registry of a nozzle with the end of an arm every time the arm advanced for positioning the label for action by the steam jet. After the application of a label to a cake of soap, the cake is advanced and rollers 105 rotating 50 on shaft 106 carried in plates 107 secured to table tops 19 and 17 by ears 108 operate on the labels to press them tightly against the paper. They are then deposited on chutes 109 and fed to belt 110 moving on pulley 111, 55 rotating on shaft 112, mounted on support 60 113 and rotatable by sprocket 114 from which chain 115 runs to sprocket 116 on main power shaft 24.
- I claim:
1. The combination of a magazine containing labels gummed on one side, means for removing said labels from said magazine with their gummed sides held outwardly and for carrying said labels to a package, and means for intermittently spraying steam upon the gummed side of said labels after the labels leave the magazine and before reaching the package, such means furnishing steam only when a label opposes it. 70
  2. In a labeling machine, a label moistener comprising a rotary nozzle having a radially extending opening therein, an apertured sleeve upon which said nozzle rotates, and means for conducting steam to said sleeve, whereby steam is intermittently projected from said nozzle when said nozzle is rotated. 80
  3. In a labeling machine, a label moistener comprising a rotary nozzle having a radially extending opening therein, an apertured sleeve upon which said nozzle rotates, means for varying the size of the aperture in said sleeve, and means for conducting steam to said sleeve, whereby steam is intermittently projected from said nozzle when said nozzle is rotated. 90
  4. The combination of rotary suction means for removing labels from a magazine, a tubular member having an opening therein and forming a support for said rotary means, and a rotary nozzle having an opening therein, said nozzle operating to discharge steam against said label. 100
  5. A moistener for labeling machines comprising a tubular member having an opening therein, a sleeve enveloping said member having an opening therein, adapted to be brought in registry with said first mentioned opening, a rotary nozzle on said sleeve having an opening therein, and means for supplying steam to said tubular member. 105
  6. The combination of a magazine, rotary means for withdrawing labels from said magazine, a tubular member having an opening therein, a sleeve having an opening therein adapted to be brought in registry with said first mentioned opening, a rotary nozzle having an opening therein, and means for bringing said nozzle adjacent to one of said labels for applying steam thereto. 115
  7. The combination of a pair of rotary nozzles, means for rotating said nozzles, a magazine, means for withdrawing labels from said magazine, and means for moving said second mentioned means in unison with said rotary nozzle, whereby steam may be applied to said labels. 125
  8. The combination of a rotary nozzle, 130

means for ejecting steam there-thru, a magazine, means for withdrawing labels from said magazine and exposing said labels to the action of the steam, said means operating to apply said labels to packages.

9. The combination of a magazine for labels, and means for supporting said magazine and permitting rotation thereof and removal of said magazine, means for remov-

ing a label from said magazine, and means for causing a simultaneous motion of said magazine and the means for removing a label.

In testimony that I claim the foregoing I have hereunto set my hand at Milwaukee, in the county of Milwaukee and State of Wisconsin.

EDWARD F. FOSTER.
